UNITED STATES PATENT OFFICE.

WALTER PELS, OF NEW YORK, N. Y.

COMBINATION FIGURE TOY AND PAINT BOX.

Application filed January 21, 1928. Serial No. 248,302.

My present invention relates generally to toys, and has particular reference to a combination toy embodying features of a doll or figure toy, and features of a paint box or 5 analogous container.

For the purpose of explaining the nature of my invention, I have illustrated and shall hereinafter describe a toy embodying the feature of my invention, wherein a container 10 is constructed to accommodate coloring materials and accessories, such as watercolors, brushes, crayons, and the like. For the sake of convenience, I have referred to the container as a paint box, but it will be understood 15 that wherever this term is used in the specification or claims, it is intended to be construed in a generic sense as defining a container for coloring materials generally or analogous articles and accessories, unless 20 the context calls for a more limited construction.

Similarly, the embodiment illustrated and described herein depicts a figure toy in the form of a fanciful human form having a 25 body, legs, arms, and a head. It will be understood, however, that as to certain phases of my invention, it is not limited to a figure of this specific character. I have therefore employed the terms "animal", 30 "limbs", and similar expressions, and wherever such terms appear they are intended to be construed in the broadest sense which the context permits.

One object of my invention is to provide 35 a paint box of novel and attractive construction, particularly one of the character which is designed primarily for use by children. One of the features of my invention lies in so constructing the box that when 40 closed the materials accommodated therein are held against accidental displacement, spilling, or the like, regardless of the particular position into which the device may be put.

Another object of my invention is to provide 45 a toy figure or doll of unique appearance, the construction being such that one portion of the doll or figure constitutes a paint box or analogous container, while 50 other portions of the doll cooperate therewith to control and facilitate the opening, closing and supporting of the container.

It is a feature of my invention to provide 55 a device wherein the torso or body of the figure toy is of an enlarged yet uniquely attractive character, and formed of adjustable

sections adapted normally to accommodate between them the materials of the paint box set. It is a particular feature to provide these sections in a complementary manner 60 whereby the external surfaces thereof normally complement each other to form a composite exterior surface of a torso. It is another feature to provide the sections with surfaces which normally are in substantial 65 abutment with each other, these surfaces being constructed with suitable recesses or depressions for the snug accommodation therein of the paints, crayons, and accessories referred to.

In one form of my invention, the body of the toy figure is substantially spherical, and the complementary sections are two in number and substantially hemispherical.

Another feature of my invention lies in 70 providing appendages upon the sections, these appendages simulating the limbs of the figure toy and being suitably positioned and constructed in accordance with this purpose. These appendages are so arranged 80 and constructed as to serve as supports for the complementary sections of the body or torso when the sections are adjusted to open the paint box or container.

In accordance with the general objects of 85 my invention, an additional appendage simulating the head of the toy figure is provided upon one of the body sections. In a preferred form, the appendage simulating the head is provided with means for 90 retaining the body sections in separable latched or closed condition.

Where the appendages are articulated to the body in an adjustable manner, it is a 95 feature of my invention to provide fastening means for the appendages and to direct these fastening means into association with the recesses previously referred to. In this way, the construction is rendered simple and expeditious.

For the attainment of the foregoing objects and such other objects as may hereinafter appear or be pointed out, I have constructed a device embodying the features of my invention and illustrated in the accompanying drawings, in which—

Figure 1 is a plan view of the device with the body sections adjusted into opened relationship; certain portions being broken away to disclose otherwise hidden parts;

Figure 2 is an elevational view of the device with the parts in the relationship

shown in Figure 1; certain portions being broken away to disclose otherwise hidden parts;

Figure 3 is an elevational view of the 5 complete device with the body sections in closed normal relationship; and

Figures 4 and 5 are fragmentary cross-sectional views respectively taken substantially along the lines 4—4 and 5—5 of Figure 1.

Referring to the drawings and for the moment to Figure 3, it will be seen that the toy figure I have illustrated as one embodiment of my invention comprises a fanciful human form having a body or torso 10 of substantially spherical configuration, an appendage 11 simulating a substantially spherical head, appendages 12 suitably constructed and positioned to simulate the arms, 20 and appendages 13 suitably constructed and arranged to simulate the legs. I have shown the arms and legs 12 and 13 constructed of jointed sections which enhance the simulation desired and permit adjustment into 25 a number of various positions. In the construction illustrated, I have also articulated the appendages to the torso 10, the particular means selected for this purpose being hereinafter described in greater detail.

30 In accordance with my invention, a portion of the toy figure constitutes a container for painting materials. I have shown the torso constructed of complementary spherical sections 14 and 15, these sections being 35 hinged as at 16 to permit relatively pivotal movement thereof to open the container. Diametrically opposite the hinge 16 I have provided a latch or fastening clip 17 for separably retaining the sections in normally 40 closed positions as shown in Figure 3. In the embodiment illustrated, one section of the latch 17 is carried by the head 11 while the complementary section 17' is carried by the body section 14. In this way, the container 45 is retained normally closed or locked, but may be opened by manipulating the head appendage 11 to separate the latch portion 17 from the complementary latch portion 17'.

50 Referring now to Figures 1 and 2, it will be seen that when the sections 14 and 15 are separated to open the container, they disclose and render accessible two surfaces 18 and 19 which are in substantial abutment 55 when the sections are closed. In a construction wherein the sections 14 and 15 are substantially hemispherical, the surfaces 18 and 19 constitute the plane faces of the hemispheres or spherical segments.

60 The surfaces 18 and 19 are provided with suitably arranged recesses or depressions for the snug accommodation of coloring or painting material and accessories. Thus, I have shown recesses 20 and 21 of substantially 65 rectangular construction adapted to

accommodate in each thereof a number of crayons 22. I have shown two elongated recesses 23 designed to accommodate accessories such as the pen 24, and brush 24'. In the particular form illustrated I have shown 70 a medial recess 25 designed to accommodate a refracting prism 26 which serves as a toy with which a child may disperse light rays into their constituent colors. I have also provided a pair of pivotal tabs or clips 27 75 which serve, in the position of Figure 1, to simultaneously enhance the retention of the elements 24, 24', and 26 in their respective recesses. The clips 27 may be pivoted into substantially parallel relationship, at 80 which time the last mentioned elements are readily removable from their recesses.

The foregoing recesses or depressions have been illustratively provided in the surface 18 of the section 14. In the complementary section 15 I have provided a set of circumferentially arranged substantially circular recesses 28 for the accommodation of vari-colored paint masses. In the center of the surface 19 I have provided a substantially circular recess 29 for the removable accommodation of a tray 30 designed to accommodate water when the device is used.

Each of the recesses 25 and 29 is provided with marginal depressions 31 which facilitate the removal of the articles accommodated.

The particular arrangement of recesses is more or less a matter of choice, but it will be noted that each of the depressions is so constructed with respect to the articles to be accommodated that the outermost exposed surfaces of the latter will arrange themselves in the planes of the surfaces 18 and 19. This is most clearly shown in Figures 100 2, 4, and 5. This construction and arrangement prevents spilling or tumbling of the accommodated articles when the sections are closed as shown in Figure 3, and facilitates the proper retention of the accommodated 105 articles in their proper places regardless of the positions into which the closed device, when used as a figure toy, may be put.

In Figure 2, I have shown one method of supporting the sections 14 and 15 in opened 110 positions. It will be noted that the leg appendages are associated with the section 14 whereas the arm appendages 12 are associated with the section 15. One possible adjustment of the appendages positions them 115 as shown in Figure 2, whereby the complementary body sections 14 and 15 are supported in the opened accessible positions shown.

Each of the appendages is preferably 120 articulated to one of the body sections in a ball and socket manner. This not only enhances the simulation of the limbs of an animal figure, but renders the construction simple and inexpensive. In the embodiment 125 il-

lustrated, I have provided fastening means which extend inwardly through the body sections into one of the recesses provided in the abuttable surfaces 18 and 19. For example, upon referring to Figure 2, it will be noted that the rear end of the appendage 13 therein illustrated is substantially hemispherical as at 32, this hemispherical end being accommodated in an adjustable manner within a similarly constructed recess 33. A bore 34 extends between the recess 33 and the recess 25, and fastening means, such as the elastic length 35 extends through the bore 34 into the recess 25. The latter is preferably lined with felt, in view of the accommodation therein of the glass prism 26. Before the felt is applied, a small sliver or wedge of wood 36 is jammed into the bore 34 to retain the length 35 therein. Subsequently, the felt is glued or similarly fastened into position and serves therefore to cover up the end of the bore 34 and the ends of the length 35 and wedge 36.

A similar construction attaches each arm 12 in an adjustable articulated manner to the section 15.

In Figure 2, I have shown an elastic length 37 held in position by means of a wedge or sliver 38, the ends of the latter being normally concealed by the pan or water container 30. In Figure 1, the dotted lines 39 illustrate a similar manner in which the head 11 may be articulated to the section 15.

It will be obvious that my invention is not limited to the provision of a spherical torso, nor to the particular arrangement of recesses arranged in the abuttable surfaces 18 and 19. In general, it will be understood that the details herein described and illustrated for the purpose of explaining the nature of my invention may be changed by those skilled in the art without departing from the spirit and scope of the invention as expressed in the appended claims. It is therefore intended that these details be interpreted as illustrative and not in a limiting sense.

Having thus described my invention and illustrated its use, what I claim as new and desire to secure by Letters Patent is—

1. A combination figure toy and box, comprising a pair of relatively movable complementary sections arranged to constitute an openable and closable container, said sections being configured to simulate the torso of a toy human figure when the container is closed, a pair of appendages on one of said sections constructed to simulate the legs of said figure, a pair of appendages on the other of said sections constructed to simulate the arms of said figure, and an appendage on one of said sections constructed to simulate the head of said figure, the leg and arm appendages being adjustable and

serving as supports for the sections when the latter are moved to open the container.

2. A combination figure toy and box, comprising a pair of relatively movable complementary sections arranged to constitute an openable and closable container, said sections being configured to simulate the torso of a toy human figure when the container is closed, a pair of appendages on one of said sections constructed to simulate the legs of said figure, a pair of appendages on the other of said sections constructed to simulate the arms of said figure, an appendage on one of said sections constructed to simulate the head of said figure, and means associated with the last-mentioned appendage for separately locking said sections in closed relationship.

3. In a combination figure toy and paint box of the character described, a pair of mutually hinged complementary sphere segments forming an openable and closable spherical container which constitutes the torso of a toy animal figure, the juxtaposed and abutting surfaces of said segments being provided with recesses for the snug accommodation of paint box materials and accessories; a pair of appendages on one segment adjacent to its recessed surface and simulating a pair of limbs of said figure, a second pair of appendages on the other segment adjacent to its recessed surface and almost diametrically opposite the first-named pair, said second pair also simulating a pair of limbs of said figure; means for separably locking said segments together; and said appendages serving as supports for said segments when the latter are unlocked and hingedly adjusted to open said container and render said materials accessible.

4. A combination figure toy and container, comprising a substantially spherical body, comprising two similar parts pivotally connected to each other slightly forwardly of the axis of the body and at the lower part thereof whereby the two pivoted body parts constitute a front body portion and a rear body portion, a clasp diametrically opposite said pivotal connection to clasp the two pivoted parts together in closed position, a head on the upper part of said front section, arms pivoted at the upper part of the sides of the front section and below the head, jointed legs pivotally attached to the lower part of the rear section, whereby when the body parts are closed the figure simulates a biped, and when the body parts are open the legs and arms may be adjusted to support the device to simulate a quadruped with portions of the legs abutting the front body section to hold the two body sections in fixed relation to each other.

In witness whereof, I have signed this specification this 19th day of January, 1928.

WALTER PEELS.
